FASTENING-INVERTING MECHANISM

Thomas H. Seely, Melrose, Mass., assignor to
United Shoe Machinery Corporation, Paterson,
N. J., a corporation of New Jersey

Application June 18, 1936, Serial No. 85,883

26 Claims. (Cl. 1—39)

This invention relates to mechanisms for inverting fastenings, and particularly to those by which nails, screws or the like are received with their heads or points arranged in one direction and are so turned that they are oppositely positioned.

Fastening-distributing apparatus, of which an example is disclosed in Letters Patent of the United States No. 1,948,499, Bertrand, February 10 27, 1934, are organized to deliver successive loads, each made up of a definite number of fastenings. Each load leaves the distributor with all its fastenings arranged with the heads or points in the same direction. In the machine by which the 15 fastenings are to be utilized, it may be desirable to receive said fastenings oppositely arranged. The present invention therefore has as an object the provision of a simple mechanism by which successively received fastenings or groups thereof 20 may be inverted by applied forces which make certain the effect sought, this mechanism being of such a character that danger of clogging is minimized. This object I attain by the employment of a movable member having a receiving 25 surface in constant fastening-receiving relation to an inclined delivery-tube or conduit, the member being movable in a direction opposite to the inclination of the conduit to effect the inversion. The movement of the inverting member is pref- 30 erably one of rotation and is best continuous, and its fastening-receiving surface is smooth and unbroken. A stop extending over the receiving surface may be used to limit the movement of the fastenings over such surface upon their discharge 35 from the delivery-conduits, and the inverted fastenings may be received by conduits opening below the member. Since the fastenings are ordinarily supplied in loads, a plurality of both the delivery-conduits and the receiving conduits with 40 their associated stops are provided, all co-operating with a single inverting member. Two forms of the inverting mechanism are especially effective. One has a cylinder rotatable about a substantially horizontal axis, while the other uti- 45 lizes a plate turning about a substantially vertical axis. In the first form, the cylinder is shown as having a groove, a delivery-conduit depositing the fastenings in the groove, while a stop extends into the groove. The plate appears as 50 provided with a downwardly and outwardly inclined marginal surface, which receives the fastenings from a delivery-conduit and has a stop extending over it. Whatever form is employed, the engagement of the receiving surface of the 55 movable member applies to the delivered fasten-

ings a constant mechanical force, as distinguished from the mere effect of gravity, through which force their inversion is brought about; and the mechanism is entirely free from fastening-receiving pockets and from passages with angularly related walls, both of which arrangements are liable to cause clogging. Great simplicity results from the use of a single movable element constantly actuated in one direction only, without the inclusion of cams or other wear-producing actuating means.

In the accompanying drawings, two of the several possible embodiments of my invention are illustrated. Here,

Fig. 1 is a vertical transverse section through one form;

Fig. 2, a full, longitudinal section on the line II—II of Fig. 1;

Fig. 3 is a top plan view of the second form, and

Fig. 4, a vertical, transverse section on the line IV—IV of Fig. 3.

Referring to Figs. 1 and 2, we have a casing 10 arranged to be secured upon the frame of a fastening-distributor or upon the machine by which the fastenings are to be used. The casing has a horizontal, cylindrical bore, and within this is arranged to turn a fastening-inverting cylinder 12 carried by a horizontal shaft 14. By this shaft, the cylinder may be rotated in the direction of the arrow in Fig. 1 in synchronism with the elements of an associated distributor (not illustrated), which delivers the fastenings to the inverting mechanism. In the cylinder is shown a series of circumferential grooves 16 situated side by side, while there may be registering grooves 18 in the casing forming therewith passages for the fastenings. Leading into each passage 16, 18, at approximately the highest portion, through the top of the casing is a short passage 20 to which delivers a tube or conduit 22 by which fastenings are conducted from the distributor to the inverting mechanism. The upper portion of the tube is shown as vertical, but, as it approaches the casing 10, it turns by a gradual bend until it enters the passage 20 at 24. Both this portion of the tube and the passage are inclined downwardly and forwardly in a direction opposite to the rotary movement of the adjacent portion of the cylinder, being substantially tangential with respect to the cylinder-passage. At the bottom of the casing is a short delivery-passage 26, from which leads a tube 27 arranged similarly to the tube 22 with a tangential portion 28 but opening from the casing at the opposite side of a vertical

plane through the axis of rotation. Through a longitudinal slot in the casing near its top is clamped a bar 30 having projections 32 extending into the cylinder-grooves 18. These projections 5 furnish stops located in the paths of the fastenings as these are discharged from the passages 20 and are at the upgoing side of the cylinder.

In the operation of the mechanism, each of the series of passages and tubes functions in precisely the same manner and may be reduced or multiplied in number in accordance with the requirements of the machine supplied. Power being applied continuously to the shaft 14, and the cylinder 12 thus being in rotation, fastenings, 15 shown in the present instance as nails N, fall points down from the distributor through the tubes 22 and are directed by the tube-portions 24 and the casing-passages 20 tangentially into the cylinder- and casing-passages 16, 18. They are 20 positively prevented from falling down the passages at the upgoing side of the cylinder by the stop-projections 32. The fastenings are then carried by the frictional engagement of the cylinder, with ample clearance for their free movement 25 but held against lateral displacement by the grooves, over the cylinder-top and are thereby inverted. At the downgoing side, they fall heads down between the inclined surfaces of the cylinder and casing under the influence of both 30 gravity and the engagement of the rotating cylinder, until they arrive at the passages 26. Into these and the tangential tube-portions 28 they are urged by their momentum and the effect of the cylinder and are delivered by the tubes 27 to 35 the machine to be supplied.

In the mechanism illustrated in Figs. 3 and 4, the actuating shaft 40 of the inverting member 42 is vertical. The member appears as a dished plate, from a depending skirt 44 of which projects in a generally horizontal direction a marginal flange 46. Upon the upper side of this flange is a downwardly and outwardly inclined fastening-receiving surface 48. Spaced uniformly about the circumference of this surface are 45 fastening-delivering tubes 50. The circumferential dimension of the surface 48 is such that it will operate properly upon fastenings of the length which are to be supplied for the number which constitute each load. The delivery-tubes 50 of this mechanism resemble the tubes 22 previously described, being inclined downwardly to points above the inverting surface 48 in a direction opposite to the rotation of said surface produced by the shaft 40, as indicated by the arrow in Fig. 3. They are preferably approximately tangential to the skirt 44 of the plate and terminate a sufficient distance above the surface 48 to permit fastenings thereon to pass freely beneath them. Surrounding the flange is a cylindrical 60 wall 52, and radially from this wall stop-projections 54 extend over the surface. There is one of these projections for each of the tubes 50 spaced forwardly from the next delivery-tube of the series with respect to the direction of rotation of the plate. Between the projections are spaces of ample length to receive in each a fastening delivered by a tube 50. The relation is clearly shown in Fig. 3. Carried in a base-plate 55, from which the wall 52 rises, is a series of receiving 65 tubes 56, one for each delivery-tube. The opening of each receiving tube is just below the outer edge of the flange 46, in advance of the opening of its delivery-tube in the direction of rotation of the plate and just at the rear of the corresponding stop-projection.

Screws S are shown in Figs. 3 and 4 as being inverted. They descend, points first, through the tubes 50 and are delivered therefrom upon the surface 48, being limited in their discharge-movement by the stops 54 toward which they are projected. When the mechanism is applied to the inversion of a plurality of screws, the stops prevent interference between screws delivered by different tubes. The rotation of the plate carries the delivered screws, in a direction opposite to that of their reception, along the inner surface 58 of the wall 52 beneath the delivery-tubes, until they reach the openings of the corresponding receiving tubes 56. Into these they fall, heads down, to the machine to be supplied. 10 Travel of each of the screws with the surface 48 beyond the receiving tube which is individual to the tube by which it is delivered may be prevented by the projection 54 adjacent to each receiving tube. These projections deflect the 20 screws into the proper receiving tube, while the wall 52, limiting movement down the inclined surface 48, holds them in the correct outward positions for delivery.

While I have chosen to describe one embodiment of this invention as applied to the inversion of headed nails and the other to screws, it is to be understood that neither is thus limited but may be utilized for either purpose or for other types of fastenings, as cut-nails, which have no 30 marked heads.

Having described my invention, what I claim as new and desire to secure by Letters Patent of the United States is:

1. A fastening-inverting mechanism comprising a fastening-delivering conduit, a rotatable member having a surface in constant fastening-receiving relation to the conduit, a conduit receiving fastenings from said surface, and means for rotating the member continuously in one direction to deposit the fastenings inverted in the receiving conduit.

2. A fastening-inverting mechanism comprising a movable member having a smooth, continuous fastening-receiving surface, a conduit delivering fastenings to the receiving surface and to which said surface is at all times presented, a conduit receiving fastenings from said surface, and means for moving the member to deposit the fastenings inverted in the receiving conduit.

3. A fastening-inverting mechanism comprising a movable member having a fastening-receiving surface, a fastening-delivering conduit inclined downwardly to a point above the receiving surface of the member, and means for moving the member with the delivered fastenings upon the receiving surface in a direction opposite to the inclination of the conduit to effect inversion of the fastenings.

4. A fastening-inverting mechanism comprising a movable member having a fastening-receiving surface, a fastening-delivering conduit inclined downwardly to a point above the receiving surface of the member, a stop extending over the receiving surface and toward which the conduit delivers the fastenings, and means for moving the member with the delivered fastenings upon the receiving surface in a direction opposite to the inclination of the conduit to effect inversion of the fastenings.

5. A fastening-inverting mechanism comprising a movable member having a fastening-receiving surface, a fastening-delivering conduit inclined downwardly to a point above the receiving surface of the member, a stop extending over the

- receiving surface at one side of the delivery-conduit, a fastening-receiving conduit opening below the member between the delivery-conduit and the stop, and means for moving the member with the delivered fastenings upon the receiving surface in a direction opposite to the inclination of the conduit.
6. A fastening-inverting mechanism comprising a movable member having a fastening-receiving surface, a fastening-delivering conduit inclined downwardly to a point above the receiving surface of the member, a fastening-receiving conduit opening below the member, the receiving surface of said member being inclined toward the receiving conduit, and means for moving the member with the delivered fastenings upon the receiving surface in a direction opposite to the inclination of the conduit.
7. A fastening-inverting mechanism comprising a movable member having a continuous fastening-receiving surface, a fastening-delivering conduit opening above the receiving surface and inclined theretoward in a direction opposite to the direction of movement, and a fastening-receiving conduit having an opening to which the receiving surface of the member delivers.
8. A fastening-inverting mechanism comprising a movable member having a continuous fastening-receiving surface, a fastening-delivering conduit opening above the receiving surface and inclined theretoward in a direction opposite to the direction of movement, a fixed wall surrounding the receiving surface, and a stop projecting from the wall over the receiving surface.
9. A fastening-receiving mechanism comprising a rotatable member, means for rotating the member continuously in one direction, and a series of fastening-delivering conduits opening above the member, each conduit being inclined downwardly toward the member in a direction opposite to the direction of rotation.
10. A fastening-receiving mechanism comprising a rotatable member, means for rotating the member continuously in one direction, a series of fastening-delivering conduits opening above the member, each conduit being inclined downwardly toward the member in a direction opposite to the direction of rotation, and a stop associated with each conduit to receive contact of the corresponding fastenings upon the member.
11. A fastening-receiving mechanism comprising a rotatable member, means for rotating the member continuously in one direction, a series of fastening-delivering conduits opening above the member, each conduit being inclined downwardly toward the member in a direction opposite to the direction of rotation, a stop associated with each conduit to receive contact of the corresponding fastenings upon the member, and a receiving conduit individual to each delivery conduit and stop.
12. A fastening-inverting mechanism comprising a cylinder rotatable about a substantially horizontal axis, a tube inclined downwardly to deliver to the surface of the cylinder about its entire circumference, and means for rotating the cylinder in a direction opposite to the inclination of the tube.
13. A fastening-inverting mechanism comprising a cylinder rotatable about a substantially horizontal axis and provided with a groove extending about its entire circumference, a tube inclined downwardly toward the groove to deliver fastenings thereto, and means for rotating the cylinder in a direction opposite to the inclination of the tube.
- cylinder in a direction opposite to the inclination of the tube.
14. A fastening-receiving mechanism comprising a casing, a cylinder rotatable in the casing about a substantially horizontal axis and provided with a circumferential groove, a fastening-delivering tube opening through the casing into the groove in a direction substantially tangential to the cylinder, and means for rotating the cylinder oppositely to the direction of introduction of the fastenings through the tangential tubes.
15. A fastening-inverting mechanism comprising a cylinder rotatable about a substantially horizontal axis and provided with a circumferential groove, a tube inclined downwardly toward the groove to deliver fastenings thereto, a stop projecting from the casing into the groove and toward which the tube delivers, and means for rotating the cylinder in a direction opposite to the inclination of the tube.
16. A fastening-inverting mechanism comprising a casing, a cylinder rotatable in the casing about a substantially horizontal axis and provided with a circumferential groove, a fastening-delivering tube opening through the upper portion of the casing into the groove in a direction substantially tangential to the cylinder, a substantially tangential tube receiving fastenings from the groove at the lower portion of the casing, and means for rotating the cylinder oppositely to the direction of entrance of the fastenings to the casing.
17. A fastening-inverting mechanism comprising a casing, a cylinder rotatable in the casing about a substantially horizontal axis and provided with a series of circumferential grooves, an inclined fastening-delivering tube opening through the upper portion of the casing opposite each groove, a fastening-receiving tube opening through the lower portion of the casing opposite each groove, and means for rotating the cylinder oppositely to the direction of inclination of the delivery-tubes.
18. A fastening-inverting mechanism comprising a casing, a cylinder rotatable in the casing about a substantially horizontal axis and provided with a series of circumferential grooves, an inclined fastening-delivering tube opening through the upper portion of the casing opposite each groove, a fastening-receiving tube opening through the lower portion of the casing opposite each groove, means for rotating the cylinder oppositely to the direction of inclination of the delivery-tubes, and a stop-bar carried by the casing and having a portion extending into each cylinder-groove.
19. A fastening-inverting mechanism comprising a plate rotatable about a substantially vertical axis, a fastening-delivering tube inclined downwardly to a point above the plate, and means for rotating the plate in a direction opposite to the inclination of the tube.
20. A fastening-inverting mechanism comprising a plate rotatable about a substantially vertical axis and having an outwardly and downwardly inclined surface, an inclined tube delivering fastenings to said surface, means for rotating the plate to carry the fastenings oppositely to the direction of inclination of the tube, and a fastening-receiving tube opening below the inclined surface of the plate.
21. A fastening-inverting mechanism comprising a plate rotatable about a substantially vertical axis and having an outwardly and downwardly inclined surface, an inclined tube deliver-

ing fastenings to said surface, means for rotating the plate to carry the fastenings oppositely to the direction of inclination of the tube, and a wall surrounding the plate and having a projection extending above the inclined surface.

5 22. A fastening-inverting mechanism comprising a plate rotatable about a substantially vertical axis and having an outwardly and downwardly inclined fastening-receiving surface, an inclined tube delivering fastenings to the receiving surface, means for rotating the plate to carry the fastenings oppositely to the direction of inclination of the tube, a fastening-receiving tube opening below the inclined surface of the plate, and a wall surrounding the plate and having a projection extending above the inclined surface of the plate and toward which the delivery-tube directs the fastenings.

10 23. A fastening-inverting mechanism comprising a plate rotatable about a substantially vertical axis, a series of fastening-delivering tubes arranged circumferentially of the plate and inclined downwardly toward its upper surface, and means for rotating the plate in a direction opposite to the inclination of the tubes.

15 24. A fastening-inverting mechanism comprising a plate rotatable about a substantially vertical axis, a series of fastening-delivering tubes arranged circumferentially of the plate and inclined downwardly toward its upper surface, means for rotating the plate in a direction opposite to the inclination of the tubes, and a

circumferential series of fastening-receiving tubes, there being a receiving tube situated in advance of each delivery-tube in the direction of rotation of the plate.

20 25. A fastening-inverting mechanism comprising a plate rotatable about a substantially vertical axis, a series of fastening-delivering tubes arranged circumferentially of the plate and inclined downwardly toward its upper surface, means for rotating the plate in a direction opposite to the inclination of the tubes, a circumferential series of fastening-receiving tubes, there being a receiving tube situated in advance of each delivery-tube in the direction of rotation of the plate, and a fastening-stop extending over the 25 plate between each pair of adjacent tubes.

25 26. A fastening-inverting mechanism comprising a rotatable plate provided with an outwardly and downwardly inclined marginal surface, a wall surrounding the plate and provided with a series of spaced projections extending over the inclined surface, a series of fastening-delivering tubes inclined downwardly to points above the marginal surface at one side of the projections, means for rotating the plate in a 30 direction from the series of projections toward the corresponding delivery-tubes, and a series of fastening-receiving tubes, each opening below the plate between the end of a delivery-tube and the corresponding projection.

THOMAS H. SEELY.
